WRENCH

Roy E. Gearhart, Kansas City, Mo., assignor of three-tenths to Richard B. McCreary and three-tenths to Byram L. McCreary, both of Kansas City, Mo.

Application June 7, 1943, Serial No. 490,106

2 Claims. (Cl. 81—89)

1

This invention relates to improvements in a wrench and particular reference to a wrench having jaws adapted to be forced toward each other during the operation.

Much difficulty has been experienced in obtaining a wrench that will remove a hard set nut and particularly a hexagon nut or screw without marring the nut or without slipping the wrench on the nut to the discomfort of its operator. Many nuts and screws are plated and need to be carefully handled to prevent damaging.

The principal object of the present invention is to provide a wrench that will so engage a nut or screw as to prevent relative movement of nut and wrench jaws and at the same time present smooth jaw surfaces against the nut thus preventing damage to the surface of the nut.

Another object of the present invention is the provision of a wrench having smooth angled jaws each of which will simultaneously contact adjacent sides of the nut.

A further object of the invention is a wrench adapted to be set to a size slightly larger than the nut to be engaged and then to be moved to clampingly engage the nut as the wrench is manually moved by its handle to loosen or set said nut.

Other objects are simplicity and economy of construction, ease and efficiency of operation, and adaptation for use on various sizes and shapes of nuts and screws.

Reference will now be had to the drawings wherein:

Figure 1 is an elevational view of a wrench embodying this invention.

Fig. 2 is an edge view of the wrench.

Fig. 3 is a sectional view taken on line III—III of Fig. 2.

Fig. 4 is an enlarged sectional view taken on line IV—IV of Fig. 1.

Fig. 5 is a fragmentary edge view showing the socket jaws of the wrench.

Fig. 6 is a side elevation of a modified form of the wrench.

Fig. 7 is an edge view of wrench shown in Fig. 6.

Fig. 8 is a sectional view taken on line VIII—VIII of Fig. 7.

Fig. 9 is a cross sectional view taken on line IX—IX of Fig. 6.

Fig. 10 is a fragmentary elevational view of a modified form of the clamping jaws.

Fig. 11 is an edge view of the jaws shown in Fig. 10.

2

Fig. 12 is an elevational view of a further modification of the wrench.

Fig. 13 is an edge view of the wrench shown in Fig. 12.

Fig. 14 is a longitudinal sectional view taken on line XIV—XIV of Fig. 13.

Fig. 15 is an enlarged cross sectional view taken on line XV—XV of Fig. 12.

Fig. 16 is a cross sectional view taken on line XVI—XVI of Fig. 12.

Fig. 17 is a fragmentary elevational view of the wrench showing a modified form of the angled jaws.

Throughout the several views like reference characters refer to similar parts and the numeral 12 designates a shank or handle having fixed jaws 14 and 16 formed in a common head and provided with angled nut engaging faces 18 and 20 respectively. Slidably mounted on shank 12 is yoke or block 22 having complementary jaws 24 and 26 having nut engaging surfaces 28 and 30 respectively to coat with surfaces 18 and 20 to engage a nut therebetween. It will be noted that the jaws 16 and 26 are constructed to serve as a socket wrench while jaws 14 and 24 are disposed at right angles thereto in the body of the head and the yoke.

Yoke 22 is recessed at 32 to present side walls 34 between which is fitted the inner end of a lever 36. This lever is pivoted to the side walls 34 by means of pivot 38, which is preferably tightly anchored in said side walls by any suitable means. A fulcrum bar 40 having a series of rack teeth 42 is secured for limited longitudinal movement between walls 34 by means of pin 44 which is fixed in the bar with its ends protruding at each side to rest in slide slots 46 which are disposed substantially parallel with the shank 12. It will be noted that ratchet teeth 42 are spaced longitudinally of the bar from the pin 44 so as to permit the hinging of the bar on the pin to free teeth 42 from the rack bar teeth 48 formed on the inner face of shank 12 (see Figures 3 and 8). Links 50 at each side of lever

36 are pivoted thereto by pivot 42 while their other ends are connected by pivot 54 to the outer end of bar 40 so that when bar 40 is in the position shown in Fig. 1 the bar teeth 42 will engage the teeth in rack bar 48 to prevent relative longitudinal movement of the bar and shank.

When so positioned the lever 36 may now be moved toward shank 12, and due to the angled relation of pivots 38, 52 and 54 and the fact that bar 40 is secured to shank 12, the yoke and associated jaws will be moved toward the respective

fixed jaws to tighten the jaws against a nut N therebetween (see nut in dotted lines in Fig. 1).

A spring 56 secured by means 58 to lever 36 passes between links 50 and rests against bar 40 so that the bar will be urged against the shank 12 to maintain the anchoring teeth in proper meshed relation during the operation of the wrench. By properly adjusting the pivots 38, 52, and 54 any desired leverage may be obtained to clamp the nut, furthermore the greater the pressure exerted on lever 36 the greater the pressure of the jaws against the nut.

When the wrench is set for operating a given size nut and the parts are positioned as shown in Fig. 5 it is desirable to maintain the setting of the wrench constant. This is accomplished by means of the detent 58 carried by lever 36 in recess 59 and urged by spring 60 into a recess 62 formed in the inner surface of wall 34, see Fig. 4. This detent will normally hold the proper setting of the wrench, however, by exerting an extra force on the lever the detent will move from recess 62 to recess 64 when the parts will be in position to permit the movement of yoke 22 on the shank for setting the jaws to fit any size nut within certain limits depending on the length of rack 48.

It will be noted that the nut engaging jaw surfaces are disposed at 120° to each other to engage the surfaces of a hexagon nut; however, this angle might be changed to fit a square nut or any other polygonal nut or any irregular nut.

Many advantages are obtained by using angled jaws, since more than two surfaces of the nut will be contacted thereby eliminating to a large degree the possibility of slipping the wrench on the nut and at the same time preventing scuffing of the nut surface. This wrench is especially adapted for use on plumbing fixtures where it is essential that the plated surfaces of the nuts be maintained in good form.

The modified form shown in Figs. 10 and 11 provides for a shank 70 having a head 72, and yoke 74 slidably mounted thereon and adapted to be operated in like manner to the parts shown in Figs. 1 to 5. The novel feature of this form is the provision of nut engaging jaws 76 and 78 having respectively two transversely intersecting angled grooves 80 and 82 thus combining the jaws of Fig. 1 in one set. At 83 the nut engaging walls of the jaws are slightly recessed to permit adjustment of the wrench on the nut.

The modified form shown in Figures 6, 7, and 8 comprises a shank 84 having an offset head 92 provided with an angled jaw 94. By referring to Fig. 7 it will be noted that the shank is relatively thin and that the jaw 94 extends outwardly at each side thereof. Shank 84 is relatively short and has a rack bar 48 on its inner wall. A block or yoke 90 is slidably mounted on shank 84 and has a transversely disposed boss 86 on which is mounted an angled jaw 88 complementing jaw 94.

Mounted in recess 96 between walls 34 is a lever or handle 36 pivoted by means of pivot 38 to said walls. A bar 40 is secured for limited longitudinal movement between walls 34 by means of pin 44 which extend into slots 46 formed in each of the side walls. This bar is provided with ratchet teeth 42 which are adapted to mesh in rack bar 48 of the shank and is interconnected to lever 36 by means of links 50. The spring 56 secured to handle 36 tends to urge bar 40 away from the lever and against the shank 84. To normally maintain the bar and shank in fixed op-

erative relation a U-shaped spring member 98 secured by screw 99 to bar 40 is adapted to engage in grooves 100 formed in the side wall of the shank (see Figs. 6 and 9).

Figures 12, 13, 14, 15, and 16 illustrate a modified form of the wrench, suitable for use as a one hand wrench, and involving the principal features of the preferred form.

This wrench comprises a shank or handle 102 terminating in a head 104 having an angled jaw 106. Yoke 108 is slidably mounted on shank 102 and is recessed at 110 to receive the end portion of lever 112 for limited pivotal movement on pivot 114. It will be noted that when the lever is in the normal position as shown the outer end portion 116 of the lever rests against the yoke wall 118 to limit the movement of the lever away from handle 102. Interposed between handle 102 and lever 112 for longitudinal movement against handle 102 is a bar 120 having a reduced end 122 which fits into a recess 124 formed in yoke 108. The outer extremity of bar 120 is notched at 126 to receive the worm 128 mounted for rotation on pin 130, and disposed in mesh with the rack teeth 132 formed on the inner face of shank 102, so that as the worm is rotated the bar will be adjusted lengthwise of the shank. To maintain the bar 120 in proper relation to the shank the bar is provided with overhanging detents 134 which slidably engage grooves 136 formed in opposite sides of the shank.

Links 138 are connected by pivot 140 to lever 112 and to bar 120 by pivot 142. It will be observed that pivots 114, 140, and 142 are not in a straight line so that when the lever is moved toward the shank the jaw 144 carried by yoke 108 will be moved toward jaw 106 to grip the nut positioned therebetween. A spring member 146 secured at its one end by screw 148 to the lever rests against bar 120 and tends to constantly urge the lever to its extended position.

This wrench may be operated by one hand to adjust the jaws to fit any given nut, and to move the nut to or from the set position.

The modified form of jaw shown in Figure 17 provides for a planar jaw face 148 formed on the head of shank 102 and a planar jaw face 150 on the yoke 108. These planar jaw faces are in parallel relation and are disposed at an angle to a planar perpendicular to the longitudinal axis of the shank 102.

This wrench is suitable for moving transversely to position on the nut N without opening the jaws any more than is accomplished by moving the lever 112 to its extended position.

From the foregoing it will be understood that various alterations in the details of construction and arrangement of parts may be made within the scope of the invention herein disclosed and claimed.

What I claim is:

1. A wrench comprising a shank having a fixed jaw; a yoke slidably mounted on said shank having a jaw complementing said fixed jaw and having side walls provided with slots disposed parallel with said shank; a rack bar formed in the face of said shank; a fulcrum bar mounted for hinge and sliding movement in the slots of said yoke; a relatively short series of teeth formed on one face of said fulcrum bar and spaced apart from the fulcrum point of said bar and adapted to mesh with the teeth of said rack bar; a lever pivoted to said yoke; a link pivotally interconnecting said lever with the free end of said fulcrum bar whereby as said lever is moved toward

said shank the fulcrum bar is urged toward said shank and said yoke is urged toward said fixed jaw.

2. A wrench comprising a shank having a fixed jaw; a yoke having slotted side walls slidably mounted on said shank and having a jaw complementing said fixed jaw; a rack bar formed in the face of said shank; a fulcrum bar mounted at its one end for pivotal and sliding movement in

the slotted side walls of said yoke; and having teeth adapted to mesh with said rack bar teeth; a lever pivoted to said yoke; links pivotally interconnecting said lever with said fulcrum bar whereby as said lever is moved toward said shank the said fulcrum bar will be urged toward said shank; and a spring interposed between said lever and fulcrum bar to normally urge them apart.

ROY E. GEARHART.
